[57] CLAIM

The ornamental design for a connector component, as shown and described.

DESCRIPTION

FIG. 1 is a perspective view of a connector component showing our new design;

FIG. 2 is a top plan view thereof;

FIG. 3 is a front elevational view;

FIG. 4 is a bottom plan view thereof;

FIG. 5 is a left side elevational view thereof; and

FIG. 6 is a rear elevational view thereof; and,

FIG. 7 is a right side elevational view thereof.

The broken lines showing through the drawings are included for the purpose of illustrating environmental structure and form no part of the claimed design.
